UNITED STATES PATENT OFFICE

2,533,188

GARMENT PRESSING MACHINE

Salvatore T. De Vitto, Chicago, Ill., assignor to
Society Brand Clothes, Inc., a corporation of
Illinois

Application May 4, 1945, Serial No. 591,946

3 Claims. (Cl. 38—15)

1

This invention relates to a machine for pressing garments and the like, and it is the object of the invention to improve such a machine so as to produce improved results. In practicing the invention, steam is employed for moistening and softening the garment and for loosening the nap of the cloth, and the garment is then shaped, pressed and dried for causing it to hold the form imparted to it. It is important that the pressure on the cloth be sufficient for thoroughly smoothing the cloth and that the cloth be dried as completely as is practical while still held in smoothed condition. It is accordingly one of the objects of the invention to provide for the prompt withdrawal of the steam from contact with the cloth after the moistening and softening effects have been attained so as to expedite the drying and permanent setting of the cloth in smoothed condition.

It is one of the objects of the invention to provide an improved pressing machine comprising means for applying a suction effect on one or both of the pressing heads of the machine throughout substantially the entire pressing operation so as to be effective for drawing the steam away from the cloth promptly after the steam has accomplished its purpose. For effecting this result, a valve has been provided for controlling the connection of the suction means with one of the pressing heads, together with means for bringing about an automatic operation of the valve for throwing the suction means into operation when the pressing heads are clamped upon a garment and for throwing such suction means out of operation when the pressing heads are released. In the preferred construction, the arrangement is such that the automatic action can readily be discontinued so as to leave the valve operable independently under the control of the workman.

It is another object of the invention to improve machines of this type in sundry details hereinafter pointed out. The preferred means by which the several objects have been attained are illustrated in the accompanying drawing in which

Fig. 1 is a vertical sectional view inside one of the side frame members of a machine embodying the invention.

Fig. 2 is a horizontal sectional view taken substantially at the line 2—2 of Fig. 1.

Fig. 3 is a diagrammatic view showing the arrangement of the valve for controlling the suction effect and the means for operating the valve.

Fig. 4 is a vertical sectional view taken sub-

stantially at the line 4—4 of Fig. 3 but shown on an enlarged scale.

Fig. 5 is a vertical sectional view taken at the line 5—5 of Fig. 1.

Fig. 6 is a view similar to Fig. 5 but showing a changed position of the parts; and

Fig. 7 is a view similar to a portion of Fig. 2 but showing a changed position of certain of the parts.

Referring now to the several figures of the drawing in which corresponding parts are indicated by the same reference characters, 10 and 12 indicate standards rising in spaced relation to each other from a base 14. Mounted upon the framework comprising the standards 10 and 12, there are two pressing heads of any appropriate type which are movable toward and from each other into and out of pressure relationship. In the arrangement shown, the lower pressing head or buck 16 is mounted rigidly in position, while the upper head 18 is mounted upon a lever 20 pivotally mounted between the standards 10 and 12 so as to be movable into and out of pressure relationship to the lower head or buck 16. As is clearly shown in Fig. 1, the head 18 is provided with a handle 22 of any approved type by which the position of the head can be readily controlled. As is shown in Fig. 3, the head 18 is hollow and is provided with a pipe or tube 24 through which live steam may be fed into the interior of the head for escape through a series of openings 26 in the pressure face of the head, the admission of steam being controlled by means of any suitable type of valve structure 28 actuated by a lever 30 (see Fig. 1).

As is also clearly shown in Fig. 3, the lower head or buck 16 is also formed hollow with a series of openings 32 in its face, such head being in communication with a duct 34 for the application of a suction effect through said openings 32.

In the arrangement shown, the duct 34 is provided with a valve 36 operated by a handle or lever 38, a coiled spring 40 being provided serving normally to hold the valve closed. The lever 38 is provided at its outer end with a vertically positioned link 42 extending downwardly to a foot lever 44 mounted in position upon a bracket 46 rising from the base 14. The head or buck 16 is also provided with a pipe 47 communicating therewith for feeding steam to the head for heating it.

In the arrangement shown, the operating lever 20 is actuated through the medium of two pivotally connected links 48 and 50, the link 50 being connected with the lever 20 by means compris-

ing a coiled spring 52 adapted to yield sufficiently for accommodating varied thicknesses of material being pressed between the heads 16 and 18. A counterweight 54 is preferably provided in adjusted position upon the outer end portion of the lever 20.

The link 48 is mounted upon a short arm forming a part of a bell crank lever 56 pivotally mounted at 58 upon the framework. Toggle links 60 and 62 are pivotally connected between link 48 and the framework of the machine comprising standards 10 and 12 and toggle link 62 is also connected by means of a link 64 with a foot lever 66 pivotally mounted on the framework of the machine. The arrangement is such that when the lever 66 is moved downwardly power is applied through the link 64 to the toggle links 60 and 62 for bringing them substantially into aligned position for pressing the power link 48 toward the left in Fig. 1 so as to move the lever 20 in clockwise direction in said Fig. 1 for pressing the head 18 against the stationary head or buck 16. The short arm of the bell crank lever 56 is supported in such operation by a lug 68 extending upwardly from the base 14.

For applying a supplemental heavy pressure effect upon the head 18, means is provided for swinging the bell crank lever 56 through a slight angle in counterclockwise direction in said Fig. 1. This means comprises toggle links 70 and 72 pivotally connected between the upper end of the lever 56 and the framework comprising the standards 10 and 12, such toggle links being pivotally connected by a link 74 with a foot lever 76 pivotally mounted upon the framework. When the lever 76 is moved downwardly so as to move the toggle links 70 and 72 into or toward aligned position with respect to each other, the bell crank lever 56 is swung in counterclockwise direction in Fig. 1 so as to raise the links 48 and 50 slightly for very substantially increasing the downward pressure of the head 18 upon the head or buck 16.

In the arrangement shown, coiled springs 78 and 80 are provided tending normally to hold the foot levers 66 and 76 in their raised positions. A dashpot 82 of any suitable type is preferably interposed between the foot lever 76 and the framework for cushioning the upward movement of the lever 76.

The arrangement is such that the toggle levers are moved into substantially aligned position by the downward movements of the foot levers so as to be self-locking in their lowered positions. For releasing the foot levers 66 and 76 when desired so as to permit them to move upwardly, a foot lever 84 is provided comprising a transversely positioned portion 86 extending underneath the lever 66 and a block 88 positioned underneath the lever 76. The arrangement is such that when the foot lever 84 is pressed downwardly the block 88 first presses the lever 76 upwardly for causing the toggle levers 70 and 72 to buckle upwardly with respect to each other, after which the transversely positioned portion 86 of the lever engages the foot lever 66 for moving it upwardly so as to cause the toggle links 60 and 62 to move into angular relationship to each other. As will be readily understood, when the links 60 and 62 are buckled upwardly, the link 48 is drawn toward the right in Fig. 1 serving to move the head 18 upwardly out of operative pressure relationship to the head 16.

In my improved arrangement, means is provided for operating the foot lever 44 automatically by the movement of levers 66 and 76. This

means comprises a cross-positioned lever 90 extending underneath the levers 66, 76 and 44 as is clearly shown in Fig. 2. This lever 90 is pivotally mounted by means of a horizontally positioned pin 92 in a bracket 94 which is frictionally rotatably mounted upon a vertical axis within a lug 96 rising from the base 14. The arrangement is such that when the levers 66 and 76 are both in their raised position as shown in Fig. 6 the lever 90 is turned to the limit of its motion in counterclockwise direction in said figure so as to permit the spring 40 to hold the valve 36 closed. When thereafter the lever 66 is pushed downwardly into the position as shown in Fig. 5, the engaged end portion of the lever 44 is moved upwardly, causing the pedal portion of the lever 44 at the right in Fig. 3 to move downwardly against the action of the spring 40 for opening the valve 36. By reason of this arrangement, the valve 36 is kept open through the entire period when the lever 66 is held in its lowered position, the valve 36 being permitted to close by the action of the spring 40 only when both levers 66 and 76 are held in their raised positions.

With the head 18 in raised position, corresponding to the raised positions of the levers 66 and 76 as shown in Fig. 6, and with the lever 90 in normal transverse position as shown in Fig. 2, a garment or other part to be pressed is arranged in position upon the buck 16. The head 18 is then moved downwardly into pressure relationship by means of the lever 66 or the levers 66 and 76, the operative downward stroke of the lever 66 serving to swing the lever 90 in clockwise direction in Fig. 6 for effecting the opening of the valve 36 so as to produce a suction effect through the openings 32 in the face of the head or buck 16. After the head 18 has been clamped in position, the valve 28 is then opened for the desired period for the ejection of steam through the openings 26 in the face of the head 18 for moistening and softening the garment or other material being pressed. By reason of the application of a suction effect continuously during the ejection of the steam and thereafter, the steam is promptly drawn through the garment and out through the head 16 so as to expedite the drying and setting of the garment in the desired shape. When at the end of the pressing operation the lever 66 is raised into the position as shown in Fig. 6, the spring 40 is permitted to close the valve 36 for terminating the suction effect through the head 16.

By reason of mounting the lever 90 upon a bracket which is rotatable about a vertical axis, the lever 90 can be swung through an angle of 90° into the position as shown in Fig. 7 for disconnecting the lever 44 from the lever 66 so as to permit the lever 44 to be operated independently of the levers 66 and 76.

While I prefer to employ the form and arrangement of parts as shown in my drawing and as above described, the invention is not to be limited thereto, except so far the claims may be so limited, it being understood that changes might well be made in the form and arrangement of the parts without departing from the spirit of the invention.

What is claimed is:

1. In a machine for pressing garments and the like, the combination of two heads, means comprising a lever for moving one of said heads into and out of pressure relationship to the other, said heads being at opposite faces of the material to

be pressed, means for ejecting steam through the face of one of said heads into contact with the material, means for subjecting the material to a suction effect through the face of the other of said heads for withdrawing the steam from the material, said suction means comprising valve means and a second lever alongside of said first named lever and operable in one direction to operate said valve means to apply the suction effect and urged in the other direction to operate said valve means to terminate the application of the suction effect, and means comprising a third lever in cross relationship to said other two levers adapted by engagement with said first and second levers to give said second lever a movement in the direction for applying a suction effect on said material when said first named lever is moved in the direction for bringing the heads into pressure relationship to each other and adapted to permit said second lever to move in the direction for terminating the application of a suction effect on said material when said first named lever is moved in the direction for separating said heads.

2. In a machine for pressing garments and the like, the combination of two heads, means comprising a lever for moving one of said heads into and out of pressure relationship to the other, said heads being at opposite faces of the material to be pressed, means for ejecting steam through the face of one of said heads into contact with the material, means for subjecting the material to a suction effect through the face of the other of said heads for withdrawing the steam from the material, said suction means comprising valve means and a second lever alongside of said first named lever and operable in one direction to operate said valve means to apply the suction effect and urged in the other direction to operate said valve means to terminate the application of the suction effect, and means comprising a third lever in cross relationship to said other two levers adapted by engagement with said first and second levers to give said second lever a movement in the direction for applying a suction effect on said material when said first named lever is moved in

the direction for bringing the heads into pressure relationship to each other and adapted to permit said second lever to move in the direction for terminating the application of a suction effect on said material when said first named lever is moved in the direction for separating said heads, said third lever being movable out of position for engagement with said first and second levers so as to leave said second lever operable independently.

3. In a steam and vacuum pressing machine, a multiple pedal control comprising a first pivotally mounted pedal controlling application of pressure, a second pivotally mounted pedal in transverse spaced relation to the first for controlling the application of suction, an intercontrol member pivoted intermediate its ends on an axis transverse to the pivot axes of said pedals and extending beneath the first pedal in advance of its pivot and under the second pedal to the rear of its pivot whereby on depression of the first pedal the rear end of the second pedal is raised to depress the second pedal in advance of its pivot, and a support for said intercontrol member mounting said member for swinging movement about an axis transverse to its pivot to permit swinging of the member from an active position between the two pedals whereby the pedals may be operated independently.
